UNITED STATES PATENT OFFICE

159,486

TABLE COVER OR SIMILAR ARTICLE

Fred Jarvis and Henry S. Bromley, Philadelphia,
Pa., assignors to North American Lace Co., Inc.,
Philadelphia, Pa.

Application December 5, 1949, Serial No. 6,414

Term of patent 3½ years

(Cl. D92—26)

To all whom it may concern:

Be it known that we, Fred Jarvis and Henry S. Bromley, both citizens of the United States of America and residents of Philadelphia, county of Philadelphia, and State of Pennsylvania, have invented a new, original, and ornamental Design for a Table Cover or Similar Article, of which the following is a specification, reference being had to the accompanying drawing, forming part thereof, wherein,

The table cover is shown over a black background to bring out the details of the design.

We claim:

The ornamental design for a table cover or similar article, substantially as shown and described.

FRED JARVIS.
HENRY S. BROMLEY.
